UNITED STATES PATENT OFFICE.

WILLIAM L. MORROW, OF STOCKTON, CALIFORNIA.

DOUBLE TWO-CYCLE ENGINE.

No. 903,753.

Specification of Letters Patent.

Patented Nov. 10, 1908.

Application filed October 25, 1907. Serial No. 399,140.

To all whom it may concern:

Be it known that I, WILLIAM L. MORROW, a citizen of the United States, residing at Stockton, in the county of San Joaquin and 5 State of California, have invented certain new and useful Improvements in Double Two-Cycle Engines; and I do declare the following to be a full, clear, and exact description of the same, such as will enable 10 others skilled in the art to which it appertains to make and use the same, reference being had to the accompanying drawings, and to the characters of reference marked thereon, which form a part of this application.

15 This invention relates to improvements in engines and particularly a double two cycle engine, the object of the invention being to produce an engine which will have a means for clarifying the explosion cylinders before 20 the new charge enters. Also an engine having a vacuum intake mechanism in the pump thereof whereby is produced a clear and pure mixture which gives the full power of 25 every explosion of the engine. This object I accomplish by means of two cylinders spaced apart and having intermediate mixing and feed chambers, ports connecting the same, a vacuum intake mechanism for said mixing chambers and by such other and further 30 construction as will appear by a perusal of the following specifications and claims.

In the drawings similar characters of reference indicate corresponding parts in the several views.

35 Figure 1 is a side elevation of the complete device. Fig. 2 is a sectional view taken on a line xx of Fig. 1. Fig. 3 is a sectional view of the complete engine taken relatively on a line yy of Fig. 2.

40 Referring now more particularly to the characters of reference on the drawings 1 designates a base box in which is journaled a shaft 2 having thereon three cranks 3, 4 and 5. Held upward from the base 1 are 45 two cylinders 6 and 7 spaced apart forming a central cylinder divided into chambers 8 and 9 by means of a center division wall 10, said wall having a centrally orificed core 11, all for a purpose as will appear. Disposed 50 in the core 11 is a rod 12 connected by a driving arm 13 to the crank 4. On the lower end of said rod 12 is a piston 14 and on the upper end a piston 15 operating in the chambers 8 and 9 respectively. Dis- 55 posed in the sides of the chambers 8 and 9 are ports 16 and 17, the port 16 being adapt-

ed to open into the chamber 8 when the piston 14 is in its lowest position and the port 17 into the chamber 9 when the piston 15 is in its highest position.

60 18 is a carbureter which has a pipe 19 entering the port 16 and a pipe 20 entering the port 17.

An upwardly inclined port 8^a leads from the upper end of the chamber 8 into the cylinder 7 while a downwardly inclined port 9^a leads from the lower end of the chamber 9 into the cylinder 6. Disposed in the cylinder 6 is a piston 21 connected by a rod 22 with the crank 3 in such manner that the piston 15 will reach its lowest position, just an instant after the piston 21 starts on its upward drive, thus keeping the pure air and gas driving from the chamber 9 into the cylinder 6 until the port 9^a is closed by the piston 21. Said piston 21 is provided with a baffle plate 23 adapted to be in front of the port 9^a when said piston 21 is in its lower position.

65 24 is an exhaust port in the side of the cylinder 6 disposed in advance of the port 9^a approximately one half inch, thereby permitting the exhaust before the new charge enters and continuing such exhaust until the port 9^a is closed, thereby permitting a thorough cleansing of the products of combustion from the cylinder. Disposed in the cylinder 7 is a piston 25 connected with the crank 3 by means of a rod 26 and in such manner that the piston 14 will reach its highest position just an instant after the piston 25 starts on its upward drive, thus 70 continuously driving pure air and gas into the cylinder 7 until the port 8^a is closed by the piston 25, all as will appear hereinafter.

75 27 is a baffle plate on the piston 25 adapted to be in front of the port 8^a when the piston 25 is in its lowest position.

28 is an exhaust port in the side of the cylinder 7 similar in construction and purpose to the port 24.

80 29 and 30 are the usual spark plugs in the cylinders 6 and 7 respectively.

In practice the piston 21 drives upward just an instant before the piston 15 drives 85 upward, thus closing the port 9^a and causing the drive of the piston 15 to make a vacuum in the chamber 9 which, when the port 17 opens, causes a sudden and effective intake of gas through the pipe 20. Then 90 with the downward drive of the pistons 15 and 21 the ports 9^a and 24 open before the

piston 15 reaches its lowest position, thus permitting the fresh charge of air and gas to be forced from the chamber 9 through port 9^a into the cylinder 6, strike the plate 23, and thus drive upward, thus forcing all the products of combustion from the cylinder 6 out through the port 24 and replacing the same with a clean, fresh charge which is suitably compressed with the upward drive of the piston and exploded by the spark plug 29, thus driving said piston as is required, said pure air and gas being continuously forced into the cylinder 6 until the port 9^a closes as has been described. The 15 pistons 14 and 25 coöperate in a similar manner as those just described, the vacuum being formed in the chamber 8, the charge of air and gas entering through the port 16 and pipe 19, the same being discharged 20 through the port 8^a driving the products of combustion in the cylinder 7 out through the port 28, and forcing air and gas from chamber 8 into cylinder 7 until the port 8^a is closed as described.

25 To produce the movement of having the pistons 14 and 15 reach their highest and lowest positions respectively after the pistons 21 and 25 start on their upward drive, which closes the ports 8^a and 9^a, I dispose the crank 4 on the shaft 2 in a manner normally obliquely to the cranks 3 and 5 as shown in Fig. 2. The core 11 may have suitable packing rings 11^a for the usual purpose.

30 In practice I fill the box 1 with a suitable quantity of lubricant which permits the cranks 3, 4 and 5 to throw the same onto the pistons, thus keeping the same automatically lubricated.

35 From the foregoing description it will be seen that I have produced an engine of the type set forth in which the explosion chambers are always clarified by the entrance of the new charge. Also one in which the in-

take of the new charge of air and gas into 45 the pump cylinders is accomplished by automatic means, namely the vacuum, as described. These two main features enable me to construct an engine having a maximum of power and minimum of speed.

50 While this specification sets forth in detail the present and preferred construction of my device, still in practice such small deviations therefrom may be resorted to as do not form a departure from the spirit of the 51 invention.

Having thus described my invention what I claim as new and desire to secure by Letters Patent is:—

1. A gas engine comprising two cylinders spaced apart, two chambers formed intermediate said cylinders, one above the other, a port leading from the lower end of the upper one of said chambers into one of said cylinders, a port leading from the upper end of said lower chamber into the other cylinder, and pistons operating in said chambers and said cylinders, as set forth.

2. A gas engine comprising two cylinders spaced apart, a chamber formed intermediate said cylinders and provided with a center division wall, a centrally orificed core in said division wall, a rod disposed through said core, a piston on each end of said rod, a crank shaft, means connecting said rod to said crank shaft, ports connecting the said chamber above and below said division wall to alternate ones of said cylinders, pistons in said cylinders connected with said crank shaft, and intake ports in said chamber adapted to be controlled by means of said pistons on said rod, as described.

In testimony whereof I affix my signature in presence of two witnesses.

WILLIAM L. MORROW.
